Walter M. Pegram
INVENTOR

UNITED STATES PATENT OFFICE.

WALTER M. PEGRAM, OF NEWBURGH, NEW YORK.

RAIL-JOINT.

1,321,844.

Specification of Letters Patent. Patented Nov. 18, 1919.

Application filed April 3, 1919. Serial No. 287,196.

To all whom it may concern:

Be it known that I, WALTER M. PEGRAM, a citizen of the United States, residing at Newburgh, in the county of Orange and State of New York, have invented a new and useful Rail-Joint, of which the following is a specification.

My invention relates to improvements in rail joints which are adapted to unite the rails of a railroad; and the object of my invention is to provide a rail joint which will hold abutting rail ends relatively in surface and alinement without the use of bolts.

15 I attain these objects by the device illustrated in the accompanying drawing, in which—

Figure 1 is a plan view of the device; Fig. 2 is a vertical end section; and Fig. 3 is a side elevation thereof.

Similar letters refer to similar parts throughout the several views.

The letter A denotes abutting rail ends; the letter B denotes angle bars engaging said rail ends A on each side thereof; and the letter C denotes a base plate provided with confronting abutments which abutments have horizontally curved seats longitudinally of said base plate C, the seats having conical surfaces for seating similarly curved and surfaced toes of said angle bars B. In the practical application of this rail joint, two bolts are used to assemble the angle bars and rail ends and to hold the rail ends against longitudinal separation; but these bolts do not maintain lateral pressure of the angle bars against the rail ends, this feature is the function of my invention, as related hereafter, and the bolts are omitted in the drawings in order to make this feature clear. The base plate is spiked to a tie in conjunction with the angle bars or the base plate, if extended longitudinally, may be spiked to a pair of adjoining ties in conjunction with the rails and these details too are omitted in drawings as they conform to conventional track practice and are like-

wise not essential to the specific functioning of my invention.

The rail ends are supported wholly by the 50 heads as the bases remain out of contact with the base plate and the pressure of a wheel load on the heads of the rail ends, reacting from the base plate through the angle bars, presses the angle bars laterally against the 55 rail ends and this pressure is sustained by the wedge-like relation between the toes of the angle bars and the seats of the abutments as disposed by the conical elements thereof and described hereafter. 60

The fishing spaces of the rail ends permit of gradual engagement of the angle bars therein, that is, the angle bars may be forced inward toward the rail webs and so it will be observed that the coned surfaces, of the 65 toes of the angle bars and of the seats of the abutments, are concentric in the initial position thereof and that because of the conical surfaces opposed in this initial position, similar radii thereof lie in the same horizontal planes. 70

It will be seen that as the toes of the angle bars are forced down between the seats of the abutments, the coned surfaces thereof are no longer concentric therebetween and 75 similar radii thereof do not all now lie in the same horizontal planes.

The effect of this derangement of concentric conical surfaces from the initial position, is to gradually diminish, at the central sectors thereof, the areas of the surfaces in contact between the toes of the angle bars and the seats of the abutments, and to concentrate the sustaining grips toward the end sectors thereof.

By virtue of the diminishing areas of the surfaces in contact between the toes of the angle bars and the seats of the abutments, whereby a slip is always imminent therebetween, the slightest readjustment of angle 90 bars and rail ends, due to wear or rust, is simultaneously absorbed by a slip downward of the toes of the angle bars on the seats of the abutments and the abutting rail ends are

continuously held, relatively, in surface and alignment by the wedge-like grip sustained toward the end sectors of the toes of the angle bars and the seats of the abutments and therebetween.

I claim:

The combination in a rail joint of two abutting rail ends, of angle bars disposed on each side thereof, of a supporting base plate 10 provided with confronting abutments for

seating said angle bars, curved bearing surfaces between the toes of the angle bars and the seats of the abutments, whereby under the weight of a wheel load, said angle bars being forced down between said abutments, 15 the areas in contact, of said curved bearing surfaces between the toes of said angle bars and the seats of said abutments, are diminished.

W. M. PEGRAM.
